(57) **ABSTRACT**

A caustic desulfonylation method and system comprising a reactor vessel with a solid carbonaceous selectivity promoter provided therein, a liquid feed input of the reactor vessel configured to receive a source of caustic, a hydrocarbon feed comprising oxidized sulfur containing compounds and a gas feed input of the reactor vessel configured to receive a source of hydrogen. The caustic desulfonylation method and system further includes an output of the reactor vessel releasing the caustic and an upgraded hydrocarbon product with sulfur content less than the sulfur content of the hydrocarbon feed received by the liquid feed of the reactor vessel.

CATALYTIC CAUSTIC DESULFONYLATION

CROSS REFERENCE TO RELATED APPLICATIONS

This application claims the priority and benefit of U.S. patent application Ser. No. 15/451,981 filed on Mar. 7, 2017, entitled "Catalytic Caustic Desulfonylation," which claims priority to U.S. Patent Application No. 62/305,039 filed on Mar. 8, 2016, entitled "Catalytic Caustic Desulfonylation," the disclosures of which are hereby incorporated by reference.

FIELD OF THE TECHNOLOGY

The following relates generally to methods and systems for performing caustic desulfonylation, and more specifically to in-situ regenerable caustic desulfonylation methods and systems.

BACKGROUND

Heavy oils and bitumens make up an increasing percentage of hydrocarbon resources. As the demand for hydrocarbon-based fuels has increased, a corresponding need has developed for improved processes for desulfurizing oil feed streams. Processes for the conversion of the heavy portions of these feed streams into more valuable, lighter fuel products have also taken on greater importance. These heavy oil feed streams include, but are not limited to, whole and reduced petroleum crudes, shale oils, coal liquids, atmospheric and vacuum residua, asphaltene, de-asphalts, cycle oils, FCC tower bottoms, gas oils, including atmospheric and vacuum gas oils and coker gas oils, light to heavy distillates including raw virgin distillates, hydrocrackers, hydrotreated oils, dewaxed oils, slack waxes, raffinates, and mixtures thereof.

Hydrocarbon streams having a boiling point above 220° C. often contain a considerable amount of large multi-ring hydrocarbon molecules and/or a conglomerated association of large molecules. These larger molecules and conglomerations often contain a large portion of the sulfur, nitrogen and metals in the hydrocarbon stream, which may be referred to as heteroatom contaminants in U.S. Pat. No. 8,764,973 to Litz et al., the contents of which are hereby incorporated by reference in its entirety, except where inconsistent with the content of the current disclosure. A significant portion of the sulfur contained in these heavy oils is in the form of heteroatoms in polycyclic aromatic molecules, comprised of sulfur compounds such as dibenzothiophenes, from which the sulfur is difficult to remove.

The processing of bitumens, crude oils, or other heavy oils with large numbers of multi-ring aromatics and/or asphaltenes can pose a variety of challenges. Conventional hydroprocessing methods can be effective at improving API for a heavy oil feed, but the hydrogen consumption can be substantial. Conversion of the liquid to less valuable products, such as coke, can be another concern with conventional techniques. Desulfurizing techniques and systems which have been disclosed by others including those systems described in U.S. Pat. No. 8,894,845 to Vann et al., U.S. Pat. No. 8,696,890 to Soto et al. and U.S. Pat. No. 8,673,132 to Leta et al., react unoxidized sulfur at high temperatures to cause thermal cracking reactions in oil. Cracking reactions convert unoxidized sulfur compounds to H₂S, resulting in the production of olefins and increases in the aromaticity which may be undesirable.

There is thus a need for a system and method for desulfurization that is capable of at least one of removing oxidized sulfur containing compounds such as sulfones, operating at lower temperatures to avoid thermal cracking reactions, producing non-ionizable hydrocarbon products while having reactants that are easily regenerated in-situ.

SUMMARY OF THE TECHNOLOGY

A first embodiment of this disclosure relates generally to a caustic desulfonylation system comprising: a reactor vessel with a solid carbonaceous selectivity promoter provided therein; a liquid feed input of the reactor vessel configured to receive a source of caustic, a hydrocarbon feed comprising oxidized sulfur containing compounds and; a gas feed input of the reactor vessel configured to receive a source of hydrogen; and an output of the reactor vessel, wherein said output releases the caustic, and an upgraded hydrocarbon product with a sulfur content less than the sulfur content of the hydrocarbon feed received by the liquid feed of the reactor vessel.

A second embodiment of this disclosure relates generally to a method for performing a caustic desulfonylation reaction comprising the steps of: providing a reactor vessel, said reactor vessel; placing, within the reactor vessel, a solid selectivity promoter made of carbonaceous material; receiving, by the reactor vessel, a hydrocarbon feed comprising a oxidized sulfur compound, a caustic and hydrogen gas; contacting the solid selectivity promoter with the hydrocarbon feed and caustic in the presence of hydrogen gas; producing an upgraded hydrocarbon product with a sulfur content less than the sulfur content of the hydrocarbon feed; and regenerating the selectivity promoter with the hydrogen gas.

BRIEF DESCRIPTION OF DRAWINGS

FIG. 1a depicts a flowchart describing an embodiment of a caustic desulfonylation treatment of a sulfone and/or sulfoxide rich hydrocarbon feed; and

FIG. 1b depicts a flow chart of an embodiment of oxidative desulfurization of a hydrocarbon feed using embodiments of caustic desulfonylation.

DETAILED DESCRIPTION OF THE DISCLOSURE

Although certain embodiments are shown and described in detail, it should be understood that various changes and modifications may be made without departing from the scope of the appended claims. The scope of the present disclosure will in no way be limited to the number of constituting components, the materials thereof, the shapes thereof, the relative arrangement thereof, etc., and are disclosed simply as an example of embodiments of the present disclosure. Reference will now be made in detail to certain embodiments of the disclosed methods and systems, examples of which are illustrated in part in the accompanying drawings and Examples below, which are provided for illustrative purposes intended for those skilled in the art and are not meant to be limiting in any way. For simplicity and clarity of illustration, reference numerals may be repeated among the figures to indicate corresponding or analogous elements.

As a preface to the detailed description, it should be noted that, as used in this specification and the appended claims,

the singular forms “a”, “an” and “the” include plural referents, unless the context clearly dictates otherwise.

Referring to the drawings, FIG. 1a, depicts a flow chart describing a system 100 and method for performing a caustic desulfonylation reaction consistent with the embodiments described herein. One or more alternative embodiments of the caustic desulfonylation system have been described and may be used as an alternative to the arrangement described in this application, so long as they are consistent with the disclosure here. For example, desulfonylation systems and equipment used to perform desulfonylation reactions described in U.S. Pat. Nos. 8,298,404 and 8,877,013 to Litz. et al., US Publication No. 2015/0337208 to Litz et al. and U.S. Pat. Nos. 8,197,671 and 8,894,843 to Rankin et al. are hereby incorporated by reference. Embodiments of the caustic desulfonylation systems and methods described herein may be performed within a reactor vessel 108. The reactor vessel 108 may be an oil/caustic reactor vessel, a promoted caustic visbreaker or a sulfone management unit in some embodiments. The reactor vessel 108 may be constructed out of any material suitable to withstand the basic conditions of the caustics being supplied to the reactor vessel 108. Examples of materials which may be suitable for constructing a reactor vessel may include iron, nickel, cobalt, and chromium based alloys and/or stainless steel alloys.

The reactor vessel 108 of the caustic desulfonylation system 100 may be configured to receive an oxidized hydrocarbon stream 111 comprising one or more oxidized sulfur containing species provided therein and/or one or more heteroatoms-containing hydrocarbons. Additional heteroatom containing compounds that may be present in the oxidized hydrocarbon stream may comprise oxidized sulfur components such as sulfoxide and sulfone rich hydrocarbons, as well as other compounds including, but not limited to those compounds comprising oxygen, nitrogen, nickel, vanadium, iron and other transition metals of the periodic table and combinations thereof. In some embodiments, the oxidized hydrocarbon stream 111 may be referred to as an oxidized heteroatom-containing hydrocarbon stream 111. The source of the oxidized hydrocarbon stream 111 may be connected to a liquid feed input (not shown) of the reactor vessel 108 allowing for the oxidized hydrocarbon stream to flow or be pumped into the reactor vessel 108 in either a metered or continuous fashion.

Inside the reactor vessel 108, the reactor vessel 108 may be provided with a solid selectivity promoter located therein. A solid selectivity promoter may refer to a substance in the solid state of matter that allows for a desulfonylation reaction to favor the production of reaction products that are non-ionizable hydrocarbon products and/or non-oxygenated hydrocarbon products. For example, the presence of a solid selectivity promoter in the reaction vessel 108 during a desulfonylation reaction may allow for the reaction to favor the production of biphenyl hydrocarbons as the dominant reaction product when dibenzothiophene sulfones are reacted. The solid selectivity promoter favors the non-ionized hydrocarbons over alternative reaction products formed by oxidized sulfur compounds such as ortho-phenyl phenolic compounds which may feature ionizable, oxygen containing hydrocarbon that may be the dominant reaction product when the solid selectivity promoter is not present. Embodiments of the solid selectivity promoter may be any solid substance that is chemically stable under the harsh basic conditions of the desulfonylation reaction and under temperatures up to about 350° C. In the exemplary embodiment, the solid selectivity promoter may be a carbonaceous

material including but not limited to activated carbon, graphite, graphene, coal or asphaltenes or combinations thereof.

Embodiments of the solid selectivity promoter may be 5 advantageous over selectivity promoters provided as a liquid or in solution because a solid selectivity promoter may remain inside the reactor vessel 108 both during and after the desulfonylation reaction has completed. Carbonaceous materials have excellent chemical resistance, and very high 10 melting points. Carbonaceous materials are rarely used as catalysts for reactions, but a solid carbonaceous material may be more effective than comparative liquid selectivity promoters and have the ability to be regenerated in-situ by hydrogen which is unusual, unexpected and highly beneficial. The carbonaceous material disclosed herein effectively 15 promotes the selectivity of the reaction to more valuable, non-ionizable hydrocarbons (e.g. dibenzothiophene sulfone to biphenyl).

Using a solid selectivity promoter and allowing it to 20 remain inside the reactor vessel 108 may be advantageous over liquid or solutions comprising a selectivity promoter. Liquids and solutions comprising selectivity promoters may be eluted from the reactor vessel during the desulfonylation reaction, and may require further separation and recycling 25 steps. Instead of being removed from the reactor vessel 108 and require further separation and recycling, a solid selectivity promoter may be regenerated inside the reactor vessel 108. In some embodiments, the solid selectivity promoter may further be advantageous because the solid selectivity 30 promoter may be continuously regenerated in-situ during the desulfonylation reaction, ensuring that that the solid selectivity promoter may not be entirely used up during a continuous desulfonylation reaction.

Embodiments of the solid selectivity promoter may be 35 regenerated by contacting the solid selectivity promoter with hydrogen gas 117. For example, in some embodiments of the desulfonylation system 100 described herein, the interior of the reactor vessel 108 containing the solid selectivity promoter may be pressurized with hydrogen gas 117. Embodiments of the reactor vessel 108 may include a gas feed input 40 connected to a source of hydrogen gas 117. The hydrogen gas 117 may subsequently be metered or pumped into the reactor vessel 108 through the gas feed input until the reactor vessel has been pressurized. The pressure of the hydrogen provided within the reactor vessel 108 may range from 45 atmospheric pressure up to about 1000 psig in some embodiments and more specifically between about 400-600 psig in alternative embodiments. In the exemplary embodiments the reactor vessel 108 may be provided with hydrogen gas to a pressure of about 200-500 psig.

Embodiments of the desulfonylation system may further 50 comprise a caustic compound 110 being provided to the reactor vessel 108 in order to perform a desulfonylation reaction. The embodiments of the caustic compound 110 may be provided to the reactor vessel 108 by connecting a source of a caustic compound 110 to a liquid feed input of the reactor vessel 108. In some embodiments, the liquid feed receiving the caustic compound 110 may be a separate liquid feed from the liquid feed input receiving the oxidized 55 hydrocarbon stream 111. In those instances where the caustic compound 110 and the oxidized hydrocarbon stream 111 each enter the reactor vessel 108 at a different liquid feed input, the liquid feed input may be referred to as a first liquid feed input, second liquid feed input, etc.

Embodiments of the caustic compound 110 being delivered 60 to the liquid feed input of the reactor vessel 108 may be any inorganic compound that exhibits basic properties. Inor-

ganic basic compounds may include, but are not limited to, inorganic oxides from group IA and IIA elements of the periodic table, inorganic hydroxides from group IA and IIA elements, or optionally mixtures of oxides and hydroxides of group IA and IIA elements, molten hydroxides of group IA and IIA elements, or optionally mixtures of hydroxides of said elements. Specific examples of the caustic compound (optionally at about 50% weight in water) may include Li_2O , Na_2O , K_2O , Rb_2O , Cs_2O , Fr_2O , B_2O , MgO , CaO , SrO , BaO , and the like as well as LiOH , NaOH , KOH , RbOH , CsOH , FrOH , $\text{Be}(\text{OH})_2$, $\text{Mg}(\text{OH})_2$, $\text{Ca}(\text{OH})_2$, $\text{Sr}(\text{OH})_2$, $\text{Ba}(\text{OH})_2$, green liquor, mixtures or molten mixtures thereof.

As shown in FIG. 1a, a desulfonylation reaction may occur when the reactants comprising the oxidized hydrocarbon stream 111 and the caustic 110 each enter the reactor vessel 108 where they mix under the pressure of the hydrogen gas 117 and make contact with the solid selectivity promoter present in the reactor vessel 108. The temperature of the reaction vessel 108 may be maintained during the desulfonylation reaction at approximately about 200-500° C. and in the exemplary embodiments between about 275-300° C. As a result of the desulfonylation reaction, a mixture of one or more reaction products may exit the reactor vessel 108 via route 114 of the desulfonylation system 100, from an output of the reaction vessel 108. The mixture of one or more reaction products exiting the reactor vessel 108 may include an upgraded hydrocarbon product 120 which may be a non-ionized hydrocarbon product, as well as the caustic, water, unconsumed hydrogen gas and sulfur containing compounds. Not intending to be bound by any particular theory, the following net equation generally describes an example of the reagents used and products observed:

In some embodiments, R and R' may even be further linked as part of a heterocyclic structure, for instance in the example of this reaction provided below:

In some embodiments, the mixture of reaction products exiting the output of the reaction vessel via route 114 may further be sent to a separating vessel 115. The separating vessel 115 may be a gravity settler in some embodiments. Inside the separating vessel 115, upgraded hydrocarbon product 120 may separate into a light phase while the water, sulfur containing compounds, residual caustic and reaction by-products may separate into a heavier dense phase 116. Subsequently, the light phase comprising the upgraded hydrocarbon products 120 can be removed and isolated from the dense phase 116. In alternative embodiments, the reaction vessel 108 may also serve as the separating vessel 115.

In some embodiments, upgraded hydrocarbon products 120 obtained and separated from the separator vessel 115 may be further washed, refined or utilized for gas, oil, fuel, lubricants or other hydrocarbon based products and further treated using known refinery processes. In some embodi-

ments, the upgraded hydrocarbon product 120 may further be washed to remove traces of reaction by-products that may not have fully separated into the dense phase. The removal of the traces of the reaction by-products such as sulfur containing compounds, and excess caustic may be removed using methods including, but not limited to, solvent extraction, washing with water, centrifugation, distillation, vortex separation, and membrane separation and/or combinations thereof. Trace quantities of caustic may also be removed using electrostatic desalting and dewatering techniques according to known methods by those skilled in the art.

Referring to FIG. 1b, in some embodiments the desulfonylation system 100 shown in FIG. 1a may be further incorporated into an oxidative desulfurization system 200 performing one or more oxidation steps to a hydrocarbon stream 101 prior to becoming the oxidized hydrocarbon stream 111 entering the reactor vessel 108. The hydrocarbon stream 101 may be combined with an oxidant 104 and subjected to an oxidation reaction inside an oxidizer vessel 102. Embodiments of the oxidation step may be carried out using at least one oxidant, optionally in the presence of a catalyst. Suitable oxidants 104 may include organic peroxides, hydroperoxides, hydrogen peroxide, O_2 , air, O_3 , peracetic acid, organic hydroperoxides may include benzyl hydroperoxide, ethylbenzene hydroperoxide, tert-butyl hydroperoxide, cumyl hydroperoxide and mixtures thereof, other suitable oxidants may include sodium hypochlorite, permanganate, biphasic hydrogen peroxide with formic acid, nitrogen containing oxides (e.g. nitrous oxide), and mixtures thereof, with or without additional inert organic solvents.

In an alternative embodiment, the step of oxidation may further include an acid treatment (not shown) including at least one immiscible acid. The immiscible acid and oxidant treatment may remove a portion of the heteroatom contaminants from the feed, wherein upon being oxidized by the immiscible acid and oxidant, the heteroatoms may become soluble in the acid phase, and be subsequently removed via a heteroatom containing by-product stream. The immiscible acid used may be any acid which is insoluble in the hydrocarbon oil phase. Suitable immiscible acids may include, but are not limited to, carboxylic acids, sulfuric acid, hydrochloric acid, and mixtures thereof, with or without varying amounts of water as a diluent. Suitable carboxylic acids may include, but are not limited to, formic acid, acetic acid, propionic acid, butyric acid, lactic acid, benzoic acid, and the like, and mixtures thereof, with or without varying amounts of water as a diluent.

In some embodiments, the oxidation reaction(s) may be carried out at a temperature of about 20° C. to about 120° C., at a pressure of about 0.1 atmospheres to about 10 atmospheres, with a contact time of about 2 minutes to about 180 minutes.

A catalyst may be used in the presence of the oxidant 104. A suitable catalyst may include transition metals including but not limited to Ti(IV), V(V), Mo(VI), W(VI), transition metal oxides, including ZnO , Al_2O_3 , CuO , layered double hydroxides such as $\text{ZnAl}_2\text{O}_4\text{x}(\text{ZnO})\text{y}(\text{Al}_2\text{O}_3)$, organometallic complexes such as $\text{Cu}_x\text{Zn}_{1-x}\text{Al}_2\text{O}_4$, zeolite, Na_2WO_4 , transition metal aluminates, metal alkoxides, such as those represented by the formula $\text{M}_m\text{O}_m(\text{OR})_n$, and polymeric formulations thereof, where M is a transition metal such as, for example, titanium, rhenium, tungsten, copper, iron, zinc or other transition metals, R may be a carbon group having at least 3 carbon atoms, where at each occurrence R may individually be a substituted alkyl group containing at least one OH group, a substituted cycloalkyl group containing at

least one OH group, a substituted cycloalkylalkyl group containing at least one OH group, a substituted heterocyclyl group containing at least one OH group, or a heterocyclylalkyl containing at least one OH group. The subscripts m and n may each independently be integers between about 1 and about 8. In some embodiments, R may be substituted with halogens such as F, Cl, Br, and I. For example, embodiments of the metal alkoxide catalyst may include bis(glycerol)oxotitanium(IV)), wherein M is Ti, m is 1, n is 2, and R is a glycerol group. Other examples of metal alkoxides include bis(ethyleneglycol)oxotitanium (IV), bis(erythritol)oxotitanium (IV), bis(sorbitol)oxotitanium (IV).

The sulfoxidation catalyst may further be bound to a support surface. The support surface may include an organic polymer or an inorganic oxide. Suitable inorganic oxides include, but are not limited to, oxides of elements of groups IB, II-A, II-B, III-A, III-B, IV-A, IV-B, V-A, V-B, VI-B, of the Periodic Table of the Elements. Examples of oxides that may be used as a support include copper oxides, silicon dioxide, aluminum oxide, and/or mixed oxides of copper, silicon and aluminum. Other suitable inorganic oxides which may be used alone or in combination with the abovementioned oxide supports may be, for example, MgO, ZrO₂, TiO₂, CaO and/or mixtures thereof. Other supports may include talc.

The support materials used may have a specific surface area in the range from 10 to 1000 m²/g, a pore volume in the range from 0.1 to 5 ml/g and a mean particle size of from 0.1 to 10 cm. Preference may be given to supports having a specific surface area in the range from 0.5 to 500 m²/g, a pore volume in the range from 0.5 to 3.5 ml/g and a mean particle size in the range from 0.5 to 3 cm. Particular preference may be given to supports having a specific surface area in the range from 200 to 400 m²/g, and a pore volume in the range from 0.8 to 3.0 ml/g.

After subjecting the hydrocarbon stream 101 to oxidation conditions in the oxidizer vessel 102, an intermediate stream 106 may be generated. A hydrocarbon feed 101 containing, for example sulfur-based heteroatom contaminants such as thiophenes, benzothiophenes, dibenzothiophenes and thioethers and others may be converted to a sulfone or sulfoxide rich intermediate stream 106. The intermediate hydrocarbon stream 106 may include oxidized heteroatom containing compounds and oxidant by-products. In some embodiments, the intermediate stream 106 may be subjected to distillation 107, for example in a distillation column. During distillation 107, the oxidized heteroatom containing compounds, may be separated from the oxidant by-products 109. The oxidant by-products may be recovered and recycled. As a result of the distillation 107, an oxidized hydrocarbon stream 111 may be formed including oxidized sulfur compounds such as sulfones and sulfoxide rich hydrocarbons. The sulfone and sulfoxide rich hydrocarbon stream 111 may be sent to the reactor vessel 108 to perform the desulfonylation reaction as described above.

Embodiments of methods for performing a caustic desulfonylation reaction, consistent with the desulfonylation system described above may be performed in accordance with the steps described herein. For instance, in some embodiments, the method for performing the caustic desulfonylation reaction may include the step of providing the reactor vessel 108 and placing within the reactor vessel a solid selectivity promoter, such as a solid selectivity promoter made of a carbonaceous material. Embodiments of the method steps may further include the step of receiving, by the reactor vessel 108, a caustic and/or hydrogen gas and an

oxidized hydrocarbon feed 111 comprising one or more heteroatom containing compounds which may include oxidized sulfur compounds.

As the reactor vessel 108 is continuously or in a metered fashion, receiving the oxidized hydrocarbon feed 111, caustic 110 and hydrogen gas 117, the oxidized hydrocarbon feed 111, caustic 110 and hydrogen gas 117 may be contacting the solid selectivity promoter. As result of the oxidized hydrocarbon feed 111 and caustic 110 contacting one another in the presence of the solid selectivity promoter, the resulting desulfonylation reaction may be producing an upgraded hydrocarbon product 120 having a reduced heteroatom content. More specifically, the upgraded hydrocarbon product 120 produced may have a sulfur content that is less than the sulfur content of the oxidized hydrocarbon feed 111. Moreover, the resulting upgraded hydrocarbon product 120 produced may be non-ionized hydrocarbon products as described above.

Furthermore, in some embodiments, as the desulfonylation system is performing the desulfonylation reaction inside the reactor vessel 108, simultaneously, or near simultaneously, the hydrogen gas 117 entering the reactor vessel 108 may be continuously regenerating the solid selectivity promoter being utilized as a desulfonylation reactant. In some embodiments, the regenerating step may also be performed by exposing the solid selectivity promoter inside the reactor vessel 108 to the hydrogen gas 117 after the desulfonylation reaction is performed.

The following working examples are provided for illustrative purposes. The working examples are intended to be non-limiting and are intended to further explain and assist in clarifying one or more of the elements of the embodiments described above in the current disclosure:

Example 1. Desulfurization of Sulfoxidized Bitumen

A 1000 mL reactor made of nickel was filled with 43.6 grams of activated carbon (3.6 moles), 45.7 grams of 50% sodium hydroxide in water, 125.7 grams of a bitumen oil containing 4.54% by weight of sulfur which had been previously subjected to sulfoxidation to convert sulfur species to sulfones (0.09 moles sulfones), and 26.6 grams of toluene as a solvent. The reactor was purged with nitrogen gas and then pressurized with 150 psig hydrogen gas (0.32 moles). The reactor was heated to 300° C. and stirred at 600 RPM for 90 minutes. The reactor was then cooled and the oil contents centrifuged to remove any caustic, activated carbon, or reaction by-products. The centrifuged oil was analyzed for sulfur content and density. The sulfur content of the bitumen was reduced by 47% from 4.54% wt sulfur to 2.41% wt sulfur. The density of the bitumen before sulfoxidation was 1.009 g/mL at 15° C., which dropped to 0.9746 g/mL at 15° C. after treatment.

Example 2. Desulfurization of Dibenzothiophene Sulfone

A 300 mL reactor made of nickel was filled with 17.1 grams of activated carbon (1.4250 moles), 17.1 grams of 50% sodium hydroxide in water, 7.7 grams of dibenzothiophene sulfone (0.0356 moles), and 50.2 grams 1,2,4-trimethylbenzene as a solvent. The reactor was purged with nitrogen gas and then pressurized with 200 psig hydrogen gas (0.12 moles). The reactor was heated to 300° C. and stirred at 600 RPM for 90 minutes. The reactor was then cooled and the product was analyzed by HPLC. All of the

initial dibenzothiophene sulfone had been converted, with 33.7 mole percent converted to biphenyl and 7.95 mole percent converted to ortho-phenylphenol.

Comparative Example 1. Desulfurization of Dibenzothiophene

An experiment was performed as in example 2, except that an un-sulfoxidized sulfur compound (dibenzothiophene) was used in place of a sulfone compound. A 300 mL reactor made of nickel was filled with 16.9 grams of activated carbon (1.4083 moles), 17.0 grams of 50% sodium hydroxide in water, 6.4 grams of dibenzothiophene (0.0348 moles), and 51.5 grams 1,2,4-trimethylbenzene as a solvent. The reactor was purged with nitrogen gas and then pressurized with 200 psig hydrogen gas (0.12 moles). The reactor was heated to 300° C. and stirred at 600 RPM for 90 minutes. The reactor was then cooled and the product was analyzed by HPLC. Only dibenzothiophene was recovered. The HPLC did not detect any reaction products.

Comparative Example 2. Desulfurization of Dibenzothiophene Sulfone without Carbon Present

An experiment was performed as in example 2, but without activated carbon present. A 300 mL reactor made of nickel was filled with 20.1 grams of 50% sodium hydroxide in water, 9.0 grams of dibenzothiophene sulfone (0.0147 moles), and 53.5 grams 1,2,4-trimethylbenzene as a solvent. The reactor was purged with nitrogen gas and then pressurized with 200 psig hydrogen gas (0.12 moles). The reactor was heated to 300° C. and stirred at 600 RPM for 90 minutes. The reactor was then cooled and the product was analyzed by HPLC. 13.87 mole percent of the initial dibenzothiophene sulfone had been converted, with 4.06 mole percent converted to ortho-phenylphenol and 0 mole percent converted to biphenyl.

Comparative Example 3. Desulfurization of Un-Sulfoxidized Bitumen

An experiment was performed as in example 1, but the bitumen was not subjected to sulfoxidation, so the sulfur in the oil had not been converted to sulfones. A 300 mL reactor made of nickel was filled with 15.0 grams of activated carbon (1.25 moles), 15.5 grams of 50% sodium hydroxide in water, 48.6 grams of a bitumen oil containing 4.54% by weight of sulfur (0.0690 moles sulfur), and 11.8 grams of toluene as a solvent. The reactor was purged with nitrogen gas and then pressurized with 200 psig hydrogen gas (0.14 moles). The reactor was heated to 300° C. and stirred at 600 RPM for 90 minutes. The reactor was then cooled and the oil contents centrifuged to remove any caustic, activated carbon, or reaction by-products. The centrifuged oil was analyzed for sulfur content and density. The sulfur content of the bitumen was only decreased by 5% from 4.54% wt sulfur to 4.32% wt sulfur.

While this disclosure has been described in conjunction with the specific embodiments outlined above, it is evident that many alternatives, modifications and variations will be apparent to those skilled in the art. Accordingly, the preferred embodiments of the present disclosure as set forth above are intended to be illustrative, not limiting. Various changes may be made without departing from the spirit and scope of the invention, as required by the following claims.

The claims provide the scope of the coverage of the invention and should not be limited to the specific examples provided herein.

5. What is claimed is:
  1. A system comprising:
    - an oxidizer vessel for oxidizing a hydrocarbon stream and thereby generating an intermediate stream;
    - a distillation column for separating oxidized heteroatom containing compounds from the intermediate stream and thereby generating a distilled oxidized hydrocarbon stream; and
  10. a reactor vessel for housing a desulfonylation reaction of the distilled oxidized hydrocarbon stream inside the reactor vessel, the reactor vessel configured such that when the desulfonylation reaction of the distilled oxidized hydrocarbon stream takes place inside the reactor vessel:
  15. a solid selectivity promoter remains inside the reactor vessel while the desulfonylation reaction of the distilled oxidized hydrocarbon stream takes place inside the reactor vessel; and
  20. the solid selectivity promoter is regenerated while the desulfonylation reaction of the distilled oxidized hydrocarbon stream takes place inside the reactor vessel.
25. 2. The system of claim 1, further comprising:
  - a separating vessel;
  - wherein the desulfonylation reaction of the distilled oxidized hydrocarbon stream results in an upgraded hydrocarbon product; and
  30. wherein the separating vessel separates the upgraded hydrocarbon product into a light phase.
35. 3. The system of claim 1, wherein the solid selectivity promoter comprises at least one of activated carbon, graphite, graphene, coal, and an asphaltene.
40. 4. The system of claim 1, wherein an interior of the reactor vessel is pressurized with a hydrogen gas.
45. 5. The system of claim 4, wherein the interior of the reactor vessel is pressurized with the hydrogen gas to a pressure of at least 200 psig.
50. 6. The system of claim 1, wherein a caustic is used in the desulfonylation reaction of the distilled hydrocarbon stream and wherein the caustic comprises an inorganic basic compound.
55. 7. The system of claim 6, wherein the inorganic basic compound includes at least one of: an inorganic oxide from a group IA or IIA element, an inorganic hydroxide from a group IA or IIA element, a mixture of oxides and hydroxides from group IA or IIA elements, a molten hydroxide from a group IA or IIA element, and a mixture of hydroxides from group IA or IIA elements.
60. 8. The system of claim 6, wherein the caustic comprises the inorganic basic compound at about 50% weight in water.
65. 9. The system of claim 6, wherein the caustic comprises at least one of: Li_2O , Na_2O , K_2O , Rb_2O , Cs_2O , Fr_2O , B_2O , MgO , CaO , SrO , BaO , LiOH , NaOH , KOH , RbOH , CsOH , FrOH , $\text{Be}(\text{OH})_2$, $\text{Mg}(\text{OH})_2$, $\text{Ca}(\text{OH})_2$, $\text{Sr}(\text{OH})_2$, $\text{Ba}(\text{OH})_2$, and green liquor.
10. The system of claim 1, wherein the intermediate stream comprises the oxidized heteroatom containing compounds and wherein the oxidized heteroatom containing compounds are formed by oxidizing the hydrocarbon stream with an oxidant in the oxidizer vessel.
11. The system of claim 10, wherein the oxidized heteroatom containing compounds are also formed by an acid treatment.

11

- 12.** The system of claim **10**, wherein a catalyst is used in the presence of the oxidant.
- 13.** The system of claim **12**, wherein the catalyst is bound to a support surface.
- 14.** The system of claim **13**, wherein the support surface ⁵ comprises one of an organic polymer and an inorganic oxide.
- 15.** The system of claim **4**, wherein the hydrogen gas regenerates the solid selectivity promoter.
